UNITED STATES PATENT OFFICE.

RAY P. PERRY, OF MONTCLAIR, NEW JERSEY, ASSIGNOR TO THE BARRETT COMPANY, A CORPORATION OF WEST VIRGINIA.

COLORED COMPOSITION SHEET.

1,296,114.

Specification of Letters Patent.

Patented Mar. 4, 1919.

Application filed June 22, 1915. Serial No. 35,533.

To all whom it may concern:

Be it known that I, RAY P. PERRY, a citizen of the United States, residing in Montclair, New Jersey, have invented certain new and useful Improvements in Colored Composition Sheets, of which the following is a specification.

This invention provides for the making of colored sheets of material to be used for roofing, flooring and similar purposes. The improvement is preferably applied to bituminous fibrous composition sheets such as are described in the patent to James C. Woodley, No. 1,166,166, granted December 28, 1915, and in other applications of said Woodley and of myself. Such composition is made by disintegrating fibrous material in intimate adhering contact with a bituminous binder, without destroying the fibrous condition of said material; the product being a homogeneous fibrous composition, non-liquefiable by heat and having other characteristics referred to in the aforesaid applications.

The present invention may be applied to other kinds of sheets, such as the reinforced sheets described in my application, No. 10,392, filed February 25, 1915, now Patent No. 1,201,756, or may be applied to the products commercially known as rubber roofing or composition roofing, with or without embedded reinforcements and in the specification and claims, the expression "bituminous composition" is intended to include compositions with or without fibers contained therein.

The invention aims to produce all of such sheets in various colors by a method which shall be economical and which shall at the same time provide a colored surface which is tough and has a good resistance to the elements when used for roofing and to wear when used for flooring. As an example, reference is made to the Woodley fibrous bituminous composition, above cited. This product cannot be satisfactorily produced in light shades by merely incorporating therewith various coloring materials. For example, if it is desired to produce a light brown or copper shade and it is attempted to incorporate in the composition sufficient pigment, such as ocher, iron oxid, etc., to produce the necessary color, it is found that the strength of the binder is deleteriously affected by the pigment and so much of the

pigment is required in order to lighten the natural dark color of the binder, such as asphalt or pitch, that the resulting sheet is extremely weak and perishable and loses many desirable properties possessed by the original uncolored composition. Also if it were possible to get a product of suitable strength by such method, it would be relatively expensive on account of the high percentage of pigment required.

My experiments have led to the discovery that this coloring of the aforesaid fibrous sheets can be satisfactorily accomplished without sacrificing any of the desirable qualities of said material and with a production of a substantially durable colored product at much lower cost as follows:

A fibrous composition is prepared by first introducing twenty parts by weight of fibrous material, such as waste paper, to eighty parts of binder, such as asphalt or pitch, of the desired consistency, and then disintegrating the fibrous material without destroying the fibrous condition so that the fibers are distributed substantially homogeneously throughout the binder and are coated and cemented together, and in some cases in part saturated by the binder, yielding a tough, fibrous composition. A portion of this composition is formed between rolls or in any other desired way into a sheet of the desired width and thickness.

A suitable pigment is mixed with another portion of the fibrous composition (or of the other known roofing compositions) in such proportions as to give the desired shade or color and the resulting mixture is rolled or otherwise formed into a sheet. This colored sheet may be of any desired thickness sufficient to wear for the required length of time under the conditions for which it is intended to be used.

A sheet of the uncolored composition is then united with a sheet of the colored composition by pressing the two together. Or if desired a sheet of the colored composition may be applied to each of the surfaces of the uncolored sheet by pressing the three together. Preferably the sheets are united shortly after being rolled into sheets while their surfaces are fresh so that they have a good cementing action. The adherence of one sheet to the other is due to their natural cementitious property. If the sheets are

colder they require a greater pressure, or if warmer they may be united by a lower pressure. If desired, the two sheets may be cemented together by a binding course of 5 melted asphalt or pitch, etc., but under proper temperature conditions and with suitable pressure, the sheets themselves can ordinarily be united satisfactorily. It will be noted that the product may have one or 10 both faces colored and yet, owing to the use of the uncolored base, we retain very considerable strength, which is desirable in a product of this kind.

If desired, a sheet of one color may be applied 15 on one face of the foundation sheet and a sheet of another color on the other face of the foundation sheet. Also the colored sheet need not be of a single color but may be made of a mottled appearance by partly 20 mixing together some uncolored composition with some colored composition and rolling the mass in a state of incomplete mixture to form a sheet; or by applying the colored composition to portions only of the face of 25 the uncolored composition, either irregularly or in a determined pattern and rolling the mass down to a smooth face. Also similar results may be obtained by combining masses of two or more differently colored compositions 30 in the same way. And the invention includes articles which are either entirely or only partially faced with the artificially colored composition.

Also a sheet of colored fibrous composition 35 may be cemented to any suitable base other than one of uncolored fibrous composition. For example, I may cement by heat or pressure, or in any other desired way, a sheet of colored fibrous composition on a 40 foundation sheet or any roofing, felt or paper, or on a plain or saturated sheet of cloth, or on a sheet of metal or of wood, or on any other foundation which has the requisite strength and other characteristics 45 required. The main idea in these cases is to use the artificially colored fibrous composition on a foundation having the required greater strength and other properties for the purpose in hand. This fibrous composition 50 has naturally greater strength than non-fibrous bituminous compositions; so that, even though weakened by the artificial coloring it is stronger than such non-fibrous bituminous composition would be when 55 similarly colored. Nevertheless, the invention may be applied with advantage to other composition roofing, as above stated; or one sheet may be of the bituminous composition and another of any of the known roofing 60 compositions above referred to.

The colored sheets are adapted to use for roofing, flooring, or siding purposes and may be put in rolls or the sheets may be cut to any desired size or cut to form shingles, tiles, etc., or other forms as desired.

The accompanying drawings illustrate diagrammatically embodiments of the invention.

Figures 1, 2 and 3 are diagrams illustrating the process; 70

Figs. 4 and 5 are respectively a section and a plan of a product having a special color applied on both faces;

Figs. 6 and 7 are respectively a section and plan of a product having one face covered 75 with a sheet of mottled appearance;

Figs. 8 and 9 are respectively a section and plan of a sheet having applied on one face separated portions of the special colored composition; 80

Fig. 10 is a plan, showing a section at one end, of a sheet having a longitudinal colored band on one face;

Fig. 11 is a perspective view of a composition shingle which can be cut from the sheet of Fig. 10; 85

Fig. 12 is a diagrammatic plan of a method of producing the sheet of Fig. 10.

The composition is formed into sheets and these sheets then pressed together to make 90 a composite sheet. The two steps of forming the sheets and uniting them may be carried out in a single operation or in separate operations. The drawings illustrate 95 both methods.

Referring first to Fig. 1, there are compression rolls A revolving in the direction indicated by the arrows and separate rolls B which compress and spread the material against the upper portions of the rolls A in 100 order to form the separate sheets. A supply of uncolored fibrous composition is maintained at C and a similar supply of the artificially colored composition at D. These bodies of the composition are in plastic 105 condition and are rolled out by the rolls A and B to form them into sheets, which sheets are carried down by the same rolling operation to the space between the compression rolls A while they are still fresh and 110 tacky and are there united by pressure to form the finished sheet E comprising the colored layer or sheet F constituting one face and the uncolored layer or sheet G constituting the other face. The individual 115 sheet-forming rolls B may be shifted toward and from the corresponding rolls A so as to regulate the relative quantities of the compositions C and D and their relative thicknesses in the sheet; and the distance 120 between the rolls A may be adjusted to vary the total thickness of the sheet.

Instead of forming the sheets and uniting them by means of the same set of rolls or at the same operation they may be first formed 125 separately and then wound upon rotatable shafts H (Fig. 2) and brought into position adjacent and parallel to the compression rolls A, the formed sheets C' and D' being then fed upon the rolls A at a point 130

somewhat in the rear of the compression point, whence they are brought together and united as previously explained by the rotation of the rolls A.

5 Or, as in Fig. 3, a spacing block B' may be arranged between and above the compression rolls A with its lower end tapered; the supply of the unformed compositions C and D being located between the respective 10 rolls and the opposite sides of the tapered block so that they are compressed against the block into individual sheets and then carried down and united by the rotation of the rolls. The spacer B' may be shifted 15 laterally and vertically to regulate the relative quantities of the compositions C and D carried down between the rolls and the relative thicknesses of the layers F and G in the composite sheet.

20 For most uses the artificial color will be required on only one side. But the process may be extended to the applying of a coating of the artificially colored composition F, F' (Figs. 4 and 5) upon both sides of a 25 layer or sheet G of uncolored composition. Or the process may be applied to two compositions artificially but differently colored so that the opposite faces of the sheet will be of different colors.

30 In Figs. 6 and 7 the uncolored sheet G has applied on one face of it a colored sheet F² of a mottled appearance produced by incompletely mixing together colored or uncolored materials or two materials which are 35 differently colored artificially.

Figs. 8 and 9 show a similar result obtained by applying on the uncolored base G separate portions F³ of artificially colored material and rolling them down to produce a 40 smooth face on the finished product.

A similar process may be used to secure a composite sheet specially adapted for use in making composition shingles in accordance with the invention described in my application for Patent No. 16,849 filed March 45 25, 1915. According to the said invention a sheet is first formed which is of varying thickness, and is preferably uniformly tapered, in cross section, and this sheet is 50 afterward cut to produce shingles thicker at one end than at the other. By the present invention a sheet may be made which is artificially colored along a portion of its face, which sheet may be cut into shingles so 55 that only the colored portions of the shingles will be exposed when they are laid with overlapping ends in the usual way. Such a sheet is indicated in Fig. 10 of greatest thickness in the center and tapering toward the opposite edges, the principal portion G⁴ of the composite sheet being of uncolored composition and an artificially colored band being formed by the layer F⁴ of artificially colored composition lying in its width across 60 the thicker portion of the composite sheet.

This sheet may then be cut along the central longitudinal line and divided by cross cuts into shingles J, Fig. 11, the exposed portion of which is composed of the artificially colored layer F⁴ and the body and covered 70 portion of which is composed of the uncolored layer G⁴. This shingle represents a combination of the greatest strength with the greatest economy.

Fig. 12 illustrates the manner of forming 75 the tapered composite sheets. The compression rolls A' are shown in plan and are of a double tapered shape, the pass being of greatest width at the center and practically closed at the ends. The separate layers are 80 previously formed into sheets C² and D² and carried on revoluble shafts H located alongside the compression rolls, and are fed while in plastic condition to the pass between the compression rolls. The sheet C² extends 85 over nearly the entire width of the pass and the sheet D² is centrally located and extends over only a fraction of the width. The sheets are made of such thickness that when compressed together they will make up the 90 desired cross section and will be compressed into tapered shape and firmly united to each other as they are carried between the compression rolls.

Various other styles of blanks may be used 95 in the manufacture of shingles. For example, the body of the blank may be made into a sheet thinner at the center and thicker at the two edges, with a band of colored material at each edge. Or the sheet may be 100 made wide enough to have several alternately thick and thin sections with colored strips along the thick sections. In these cases there would be not only one but several strips of the colored material.

Various other modifications of the product and process as described may be made by those skilled in the art without departing from the invention as defined in the 105 following claims.

What I claim is—

1. As a new article of manufacture the combination of a plurality of pre-formed sheets of bituminous composition united face to face, at least one of which is artificially colored.

2. As a new article of manufacture the combination of a plurality of pre-formed sheets of bituminous composition united face to face, one of said sheets being uncolored 120 and another constituting the face of the article and being artificially colored.

3. As a new article of manufacture the combination of a plurality of sheets of bituminous composition united face to face, at 125 least one of said sheets being artificially colored and another being of a fibrous character.

4. As a new article of manufacture the combination of a plurality of sheets of bi- 130

tuminous composition united face to face, one of said sheets constituting the foundation and being of fibrous character and uncolored, and another of said sheets constituting the face of the article and being artificially colored.

5. As a new article of manufacture the combination of a plurality of sheets of bituminous composition united face to face to 10 form a composite sheet, at least one of which is artificially colored and of less extent than another so as to constitute only a portion of the face of the composite sheet.

6. As a new article of manufacture the combination of a plurality of sheets of bituminous composition united face to face to 15 form a composite sheet, at least one of which is artificially colored and of less width than another so as to constitute a longitudinal 20 colored band extending along the face of the composite sheet.

7. As a new article of manufacture the combination of a plurality of sheets of bituminous composition united face to face to 25 form a composite sheet of varying thickness in cross section, at least one of said sheets being artificially colored, of less width than the composite sheet and constituting a longitudinal colored band extending along 30 the face and lying in width across the thicker portion of the composite sheet.

8. As a new article of manufacture the combination of a plurality of preformed sheets united face to face, of which at least one is of uncolored fibrous bituminous composition and at least one is of artificially colored waterproofing composition.

9. As a new article of manufacture the combination of a plurality of preformed sheets of bituminous composition, non- 40 liquefiable by heat, united face to face, at least one of which is artificially colored.

10. As a new article of manufacture the combination of a plurality of preformed sheets united face to face, one of said sheets 45 being made substantially of paper fibers and asphalt and another of said sheets being made of an artificially colored waterproofing composition.

11. As a new article of manufacture for 50 roofing and the like, the combination of a plurality of pre-formed sheets adhering face to face, of which one is an uncolored fibrous bituminous sheet and another is of artificially colored waterproofing composition, 55 non-liquefiable by heat, some portions of this colored sheet being of one color and other portions of another color.

In witness whereof, I have hereunto signed my name.

RAY P. PERRY.
